PUNCH

Kay L. Ruggles, Salt Lake City, Utah, assignor to Bio-Logics, Inc., Salt Lake City, Utah, a corporation of Delaware

Filed Aug. 13, 1969, Ser. No. 18,671

Term of patent 14 years

Int. Cl. D8—02

U.S. Cl. D8—52

FIG. 1 is a perspective view of a punch embodying my new design illustrating primarily the bottom of the punch;

FIG. 2 is one side elevational view of the punch of FIG. 1;

FIG. 3 is the other side elevational view of the punch of FIG. 1;

FIG. 4 is a bottom plan view of the punch of FIG. 1;

FIG. 5 is a top plan view of the punch of FIG. 1;

FIG. 6 is a front elevational view of the punch of FIG. 1; and

FIG. 7 is a rear elevational view of the punch of FIG. 1.

I claim:

The ornamental design for a punch, substantially as shown.
